His Attorney.

UNITED STATES PATENT OFFICE.

EDWARD D. PRIEST, OF SCHENECTADY, NEW YORK, ASSIGNOR TO GENERAL ELECTRIC COMPANY, A CORPORATION OF NEW YORK.

COVER-HINGE FOR ELECTRIC MACHINES.

1,331,874.

Specification of Letters Patent. Patented Feb. 24, 1920.

Application filed December 17, 1917. Serial No. 207,516.

To all whom it may concern:

Be it known that I, EDWARD D. PRIEST, a citizen of the United States, residing at Schenectady, county of Schenectady, State 5 of New York, have invented certain new and useful Improvements in Cover-Hinges for Electric Machines, of which the following is a specification.

My invention relates to cover-hinges for 10 electric machines and particularly for such machines when used as motors for propelling vehicles.

It is usual to mount such motors underneath the vehicle frame and in close proximity thereto. The frames of such motors are provided with openings adjacent the commutators in order that access may be had to the interior of the motor for inspecting and repairing the commutators, brushes and 15 brush-holders. These openings are provided with covers for protecting the interior of the motors. My invention has for its object the provision of an improved cover-hinge of a novel and simple construction, 20 whereby with the coöperation of a latch at the opposite end the cover is securely held in position during the operation of the motor and whereby the cover may be readily removed upon the release of the latch, when 25 the motor is not in operation, without raising it but a few inches.

The various features of novelty which characterize my invention are pointed out with particularity in the claim annexed to 30 and forming a part of this specification. For a better understanding of my invention, reference may be had to the following description taken in connection with the accompanying drawing, in which Figure 1 is a 35 sectional view of a portion of the frame of a railway motor provided with my invention; Fig. 2 is a view, similar to Fig. 1, with my cover partially released, and Fig. 3 is a view with my cover entirely released.

Referring to the drawing, 1 is a portion 40 of the frame of a railway motor, at the commutator end thereof, which is provided with an opening 2 through which access may be had to the commutator, brushes and brush-holders (not shown). This opening is provided with a metal cover 3. Fastened to the

frame adjacent one end of the opening is an eye-bolt or a staple 4.

Fastened to the cover at a point inwardly from the edge thereof is a resilient extension 55 piece 5, bent back upon itself to form a hook, the opening 6 of the hook being on the under side of the extension piece 5. The hook engages the staple 4 and thus forms with the staple, a hinge for the cover 3. 60 The cover has a lip 7 extending completely about the cover and over the outside edge 8 of the opening 2 so as to prevent the leakage of dust and water into the motor. A locking device is provided at the end of the cover 65 away from the extension piece 5, for firmly and tightly locking said cover in place. In the particular arrangement shown, the locking device comprises a spring member 9 fastened to the cover 3 and a lever 10 pivoted on the motor frame and having a link 11 pivoted to the lever 10. In the locked position, the end 12 of the link engages the end of the spring member 9, the lever being 70 rotated into the position shown in Fig. 1. 75

By making the extension piece 5 and the member 9 of resilient material, and by providing the cover with the lip 7, it will be securely locked in position with the parts in 80 the position shown in Fig. 1, so that it can not move during the operation of the motor.

In order to remove the cover, the lever 10 is rotated into the position shown in Fig. 2, thereby releasing the engagement between the link 11 and the member 9. The cover 85 can now be tilted into the position shown in Fig. 2, and then moved backwardly so that the hook formed by the extension piece will clear the staple 4. The cover can then be lifted vertically a distance of a few inches 90 into the position shown in Fig. 3. It may then be entirely removed from the motor by moving it horizontally. It will thus be seen that with my construction of cover-hinge it is possible to remove the cover without lifting or tilting it but a few inches, which is a 95 great advantage when the motor is mounted underneath a vehicle and in close proximity to the under side of the vehicle frame.

What I claim as new and desire to secure 100 by Letters Patent of the United States, is,—

The combination with a motor frame hav-

ing an opening and a removable cover there-
for, of a hinge for said cover comprising a
staple fastened to said frame adjacent said
opening, and a resilient extension piece fas-
tened to said cover at a point inwardly from
the edge of said cover and bent back upon
itself to form a hook, the opening of said

hook being on the underside of said exten-
sion piece, said hook being adapted to en-
gage said staple.

10

In witness whereof, I have hereunto set
my hand this 14th day of December, 1917.

EDWARD D. PRIEST.
